UNITED STATES PATENT OFFICE.

JAMES CRAWFORD AND JOSEPH H. YOUNG, OF BOSTON, MASSACHUSETTS.

FLUSH-TANK FOR WATER-CLOSETS.

SPECIFICATION forming part of Letters Patent No. 536,851, dated April 2, 1895.

Application filed September 28, 1894. Serial No. 524,363. (No model.)

To all whom it may concern:

Be it known that we, JAMES CRAWFORD and JOSEPH H. YOUNG, citizens of the United States, and residents of Boston, in the county 5 of Suffolk and State of Massachusetts, have jointly invented new and useful Improvements in Flush-Tanks for Water-Closets, of which the following, taken in connection with the accompanying drawings, is a specification.

10 This invention relates to improvements in flush tanks for water closets, and it relates to that class of devices in which a fore and after wash is produced respectively at the time of depressing the seat of the water closet and at 15 the time and after leaving it, as will herein-after be more fully shown and described, reference being had to the accompanying drawings, wherein—

Figure 1 represents a top plan view of the 20 invention, showing it in its normal position. Fig. 2 represents a longitudinal section on the line 2—2 shown in Fig. 1. Fig. 3 represents a sectional view showing in full lines the positions of the flush tank levers during 25 the depression of the seat and showing in dotted lines the said parts in position at the time the occupant leaves the seat of the water closet. Fig. 4 represents an end view of the flush tank and water closet as seen from X in 30 Fig. 1. Fig. 5 represents a detail top plan view of one of the seat supporting brackets; and Fig. 6 represents a longitudinal section on the line 6—6 shown in Fig. 5.

Similar letters refer to similar parts wherever they occur on the different parts of the 35 drawings.

A in Fig. 4 represents the water closet bowl as usual, and B in said figure represents the upright wall of the room in which the water 40 closet is located. To said walls are secured in a suitable manner brackets C C, one on each side of the bowl as is common in devices of this kind.

D is the perforated seat as usual, the rear 45 end of which is hinged at d (Fig. 4) to adjustable bearings C' C', secured to the brackets C, C, as shown in Figs. 5 and 6. For the purpose of properly adjusting the seat D relative to the bowl A it is essential that the bearings 50 C', C' should be adjustable relative to the brackets C C, and for this purpose each of said brackets is provided with a longitudinal

slot C'', through which projects a bolt C³, attached to the bearing C', which is adjustably secured in the slot C'', of the bracket C by 55 means of the nut C⁴, as shown in Fig. 6.

E is the flush tank as usual secured in a suitable manner at a proper distance above the bowl A as shown in Fig. 4.

F is the water supply pipe leading from any 60 suitable water pressure source as usual and provided with a valve f which when open allows the water to flow through pipe f' into the tank E as usual.

The admission of water to the tank E is 65 regulated by a hollow ball float G, connected to a lever g, pivoted at g' and having a projection g'', adapted to close the valve f when the proper quantity of water is fed into the tank E as is common in devices of this kind. 70

H is the discharge pipe leading from the bottom of the tank E to the rear of the water closet bowl A, as usual, which is normally closed by means of a valve I to which is attached a valve rod i and tube i' as usual. 75

K is the bracket secured to the upper end of the tank E, and to said bracket is pivoted at k the lever L, to which is connected the rod l, the lower end of which is pivoted to the rear end of the seat lever M, which is pivoted 80 at m to one of the seat brackets C and provided at its forward end with a roller m', (shown in Fig. 4) against which the pivoted seat D is normally made to rest, as fully shown in Fig. 4. To the pivot k of the lever 85 K is secured a crank k' having a roller k'' journaled on a stud attached to its end as shown in Figs. 1, 2, 3 and 4.

N is a lever pivoted at n in a bracket secured to the tank E and to one end of said lever 90 is pivoted the valve stem i as shown in Figs. 1, 2, and 3. The other, or free end of said lever N is preferably provided with a wedge shaped projection N' which is actuated by the roller k'' on the crank k' and intervening 95 automatic mechanism so as to open and close the valve I with a comparatively quick motion, when the seat D is depressed, and to open said valve and close it with a comparatively slow motion as soon as the pressure 100 on the seat D is removed, thus causing a light fore wash of the water from the tank E to enter the bowl previous to using it and an increased and prolonged after wash to be forced

into the bowl as soon as a person leaves the seat.

The intervening automatic mechanism above mentioned consists of a weighted lever 5 O pivoted at O' and having on its under side notches or recesses O'', O³, adapted to receive a pin or pin and roll n', on the lever N as shown in Figs. 2 and 3.

O⁴, in Fig. 1, is a side projection on the 10 weighted lever O against which the roller k'' comes in contact to raise said lever O to its highest position shown in full lines in Fig. 3, when the seat D is depressed and during such depression of said seat the roller k'' on the 15 crank k' comes in contact first with the valve lever projection N' causing the valve I to be opened during such motion and held temporarily so by the pin n' entering the notch O³ in the weighted lever O; and as the roller k'' reaches its right hand position shown in Fig. 20 3 it comes in contact with the side projection O⁴ on the lever O by which the latter is raised sufficiently to liberate the valve lever N and close its valve I, and during such closing 25 movement of the lever N the weighted lever O assumes the position shown in full lines in Fig. 3 with the pin n' on the lever N as received in the notch O'', on the lever O as shown in the said full lines of Fig. 3. The notch O'' is 30 however not essential as it is only necessary that the pin n' should serve as a rest or support for the lever O while in this position.

When the occupant leaves the seat D the lever L and its crank k' are automatically moved from the position shown in full lines 35 in Fig. 3 to the normal position shown in dotted lines in said Fig. 3, and during such return motion the roller k'' comes in contact with the projection N' on the valve lever N 40 by which the valve I is opened and held so by the weighted lever O, the notch O³ on which receives the pin n' of the valve lever N and thereby holds the valve lever in the open position shown in dotted lines in Fig. 3, thus 45 causing a comparative long after wash to be conducted from the tank E to the water closet bowl A. During such "after wash" as the water from tank E flows out through pipe H, the float G gradually sinks and its lever g 50 comes in contact with a bent wire P attached to the weighted lever O causing the latter to be slightly raised sufficiently to disengage the valve lever pin n' from the locking notch O³ on said lever O by which the valve lever N is 55 released and allowed to assume its normal closed position by which the discharge valve I is closed.

During the fall of the float G the supply valve f is automatically opened causing a

proper supply of water to the tank E until 60 the float G is raised by the water in the tank E to its highest normal position, when the supply is automatically cut off, by the closing of the valve f, and so on during the operation 65 of the device.

What we wish to secure by Letters Patent and claim is—

1. In a flush tank for water closets, a discharge valve and a pivoted lever connected thereto and carrying a pin n', combined with 70 a crank actuated by the movable bowl seat and operating to open the discharge valve when the seat is depressed or raised, a pivoted weighted lever O having a recess o³ adapted to engage the pin n' and temporarily hold the 75 discharge valve open to produce a preliminary wash, a projection carried by said weighted lever and engaged by said crank at the end of the movement of the latter to release and close said discharge valve, and a pivoted float lever controlling a water supply pipe and operating to release and close the discharge valve at the end of the after wash, substantially as described.

2. In a flush tank for water closets a supply 85 cock float and flush valve combined with a pivoted valve lever N, having a projection n', a crank k' actuated by the bowl seat and a pivoted weighted lever O having a recess O³ adapted to engage the valve lever pin n' and 90 having a projection O⁴ adapted to engage with the crank k', and having a downward extension P, adapted for engagement with a float lever for releasing the valve lever at the end 95 of the after wash substantially as and for the purpose set forth.

3. In a flush tank for water closets, a pivoted valve lever N connected to the discharge valve and having a cam shaped projection N' and a locking projection n', combined with a weighted pivoted and notched lock lever O having a downward extension P and a lateral projection o⁴, a crank actuated by the yielding seat D and adapted to impart a yielding motion to the valve lever and lock lever for 105 opening and closing the valve with a fore and after variable wash, and a float for engaging the extension P at the end of the after wash to close the valve, substantially as described.

In testimony whereof we have signed our names to this specification, in the presence of two subscribing witnesses, on this 24th day of September, A. D. 1894.

JAMES CRAWFORD.
JOSEPH H. YOUNG.
